WILLIAM KIMELMAN, OF MCKEESPORT, PENNSYLVANIA, ASSIGNOR OF ONE-HALF TO
FRANK R. S. KAPLAN, OF MCKEESPORT, PENNSYLVANIA.

DEVICE FOR STAMPING ENVELOPS.

1,189,831.

Specification of Letters Patent.

Patented July 4, 1916.

Application filed February 4, 1916. Serial No. 76,137.

To all whom it may concern:

Be it known that I, WILLIAM KIMELMAN, a citizen of the United States, residing at McKeesport, in the county of Allegheny and State of Pennsylvania, have invented certain new and useful Improvements in Devices for Stamping Envelops, of which the following is a specification.

The invention relates to a device for stamping envelops or the like. It has for its primary objects the provision of an improved device for positioning the envelops, blotting them, moistening the corners, and applying the necessary pressure to affix the stamps after they are placed in position; and the provision of a device simple in construction, and neat in appearance which can readily be used in connection with an ink bottle holder and pen rack. One embodiment 20 of the invention is illustrated in the accompanying drawings, wherein—

Figure 1 is a plan view of the device, Fig. 2 is a front elevation, and Fig. 3 is an end elevation.

Referring to the drawings, 1 is the base plate provided with four legs 2. Above this base plate is what may be termed a presser plate 3, such plate carrying four depending posts 4 which extend slidably 30 through the base plate. The presser plate is provided on its upper surface with small blocks 5 into which the upper ends of the posts 4 are screwed, the lower ends of the posts being provided with heads to prevent 35 the accidental removal of the presser plate from the base plate.

The opposing faces of the presser and base plates are provided with blotters 6 and 7, and the corner of the presser plate is cut 40 away, as indicated at 8 in Fig. 1, to expose the corner of an envelop 9 when held between the two plates. The presser plate is also provided with a handle 10 so that it may be conveniently moved up and down.

Mounted opposite the cut away corner 8 of the presser plate is the moistening pad consisting of a top plate 11 carrying on its lower side a moisture retaining pad 12 of felt or some other material suitable for the 50 purpose. This pad is guided for lateral movement in a member 13 of inverted U-shape in cross-section, as indicated in Fig. 3, such member being secured to the base plate by means of the screws 14. The 55 top of the member 13 is provided with a slot

15 (Fig. 1), and a thumb screw 16 is provided with a shank 17 (Fig. 3) which fits in the slot 15 and has its lower end screw-threaded into the plate 11 carrying the felt or pad 12. A spring 18 is interposed between the top of the member 13 and the under side of the head of the thumb screw. This spring causes the plate 11 to engage the lower side of the member 13 while at the same time permitting the pad to be compressed to provide the required amount of moisture when the thumb screw is forced down. A small plate 19 is preferably provided beneath the pad 12 (Fig. 3).

The base plate is also provided with four 70 up-standing corner members 20 to receive an ink bottle 21, and the front side of the base plate is provided with the depending brackets 22 having the hooked portions 23 and constituting a pen rack. The material 75 employed in the construction of the device is preferably sheet metal of some kind, either aluminum, brass, or sheet iron covered with some appropriate coating.

In operation, after a letter has been addressed, it is placed between the two plates and the upper plate moved down, thus gripping the envelop between the two plates. The posts 4 not only guide the presser plate but also act as positioning means for the envelop whose edges are indicated by the dotted lines 24 in Fig. 1. The upper presser plate blots the envelop, thus rendering unnecessary any blotting before the envelop is placed between the plates. After 90 the envelop is positioned, as indicated in Fig. 1, the thumb screw 16 to which the moistening pad is secured is grasped, and the pad is moved to the left over the exposed corner 9 of the envelop. The plate 95 19 raises the lower surface of the pad 12 so that it is at the same level as the upper surface of the envelop and therefore, does not catch on the edge of the envelop as the pad is moved to the left. The spring 18 permits 100 the pad to be compressed after it is moved over the corner 9 to give the necessary degree of moistening. After the pad is moved back to its starting position, the stamp is applied to the corner 9 and the envelop 105 moved partially out so that the corner 9 with the stamp comes beneath the plate 3, when the plate is pressed down to apply the necessary pressure to the stamp. The provision of the legs 2 to give elevation to the 110

plate 1 is advantageous as it provides the space for the guide posts 4 and for the pen rack brackets 22. The ink bottle holder is located upon a portion of the base plate 5 which would otherwise be superfluous, but which is necessary in order to make the plate symmetrical and because of the moistening device. The device can be used with envelopes of any size since the exposure of the 10 part to which the stamp is to be applied is the same regardless of the size of the envelop, and the moistening pad may be kept damped a relatively long period when withdrawn into its casing 13. It may be 15 readily taken out for re-wetting by removing the thumb screw 16. If desired, the sealing of the envelop can be accomplished at the same time that the blotting and stamping is accomplished, or this may be 20 done separately at another time. Various other advantages incident to my invention as an improvement in stationary devices will readily be apparent to those skilled in the art.

25 What I claim is:

1. In combination in a device for stamping envelopes, a base member for supporting an envelop, a moistening pad mounted for movement over the corner of an envelop 30 when supported on the base member, and a presser plate member mounted for movement toward and from the base member and cut away at the portion opposite the moistening pad whereby the pad may be moved over the corner of the envelop when it is held between the base and plate members.
2. In combination in a device for stamping envelopes, a base member for supporting an envelop, a moistening pad mounted for movement over the corner of an envelop 40 when supported on the base member, and a presser plate member mounted for movement toward and from the base member and cut away at the portion opposite the moistening pad whereby the pad may be moved over the corner of the envelop when it is held between the base and plate members, the presser plate member having a blotter on its lower face.
3. In combination in a device for stamping envelopes, a base member for support-

ing an envelop, a moistening pad mounted for movement over the corner of an envelop when supported on the base member, a presser plate member upon the base member, and posts for guiding the plate member vertically and arranged to position the envelop upon the base member, the said plate member being cut away at the portion opposite the moistening pad whereby the moistening 60 pad may be moved over the corner of the envelop when it is held between the base and plate members.

4. In combination in a device for stamping envelopes, a base member for supporting 65 an envelop, a moistening pad mounted for sliding movement laterally over the corner of an envelop when supported on the base plate, and a presser plate above the base plate guided for vertical movement and 70 having its corner cut away at the portion of the plate member which would otherwise come over the corner of the envelop to be stamped.

5. In combination in a device for stamping 75 envelopes, a base member for supporting an envelop, a moistening pad guided for lateral movement over the corner of an envelop when supported on the base member and also having a limited vertical movement, and a presser plate member mounted for movement toward and from the base portion and cut away at the portion opposite the moistening pad whereby the pad may be moved over the corner of the envelop 85 when it is held between the base and plate members.

6. In combination in a device for stamping envelopes, a base member for supporting 90 an envelop, a moistening pad guided for lateral movement over the corner of an envelop when supported on the base member and also having a limited vertical movement, a spring for holding the moistening pad at its upper limit of movement, and a 95 presser plate member mounted for movement toward and from the base portion and cut away at the portion opposite the moistening pad whereby the pad may be moved over the corner of the envelop when it is 100 held between the base and plate members.

WILLIAM KIMELMAN.
